UNITED STATES PATENT OFFICE

117,322

DESIGN FOR A SEAT SPRING UNIT

Edward W. Schlappritz, Minneapolis, Minn.

Application June 28, 1939, Serial No. 85,743

Term of patent 14 years

To all whom it may concern:

Be it known that I, Edward W. Schlappritz, a citizen of the United States of America, residing at Minneapolis, in the county of Hennepin and State of Minnesota, have invented a new, original, and ornamental Design for a Seat Spring Unit, of which the following is a specification, reference being had therein to the accompanying drawing, forming a part thereof, wherein:

Figure 1 is a top perspective view of a seat spring unit showing my design;

Figure 2 is a bottom perspective view thereof;

Figure 3 is an edge elevation thereof.

I claim:

The ornamental design for a seat spring unit, substantially as shown.

EDWARD W. SCHLAPPITZI.
